UNITED STATES PATENT OFFICE.

ANDREW EPPLER, JR., OF NEWTON, MASSACHUSETTS.

STITCH SEPARATING AND INDENTING MACHINE.

SPECIFICATION forming part of Letters Patent No. 611,571, dated September 27, 1898.

Application filed February 1, 1897. Serial No. 621,446. (No model.)

To all whom it may concern:

Be it known that I, ANDREW EPPLER, Jr., of Newton, in the county of Middlesex and State of Massachusetts, have invented certain new and useful Improvements in Stitch Separating and Indenting Machines, of which the following is a specification.

This invention has relation to "pricking-up" machines or machines for indenting the exposed part of the welt for the purpose of separating and bringing out the stitches in bold relief.

The object of the invention is to provide a machine of this character equipped with such improvements that the indenting-tool will accurately separate or prick up the stitches regardless of slight variations in their lengths; and it consists of a machine equipped with those features of improvement illustrated upon the drawings, and which I shall now proceed to describe in detail and then point out in the claims hereto annexed.

Reference is to be had to the annexed drawings, and to the letters marked thereon, forming a part of this specification, the same letters designating the same parts or features, as the case may be, wherever they occur.

Of the drawings, Figure 1 is a plan view of an indenting-machine equipped with my improvements. Fig. 2 is a side elevation of the same. Fig. 2^a is an elevation from the other side. Fig. 3 is a front elevation of the machine. Fig. 4 is a transverse sectional view of the same taken on the line 4 4 of Fig. 1. Fig. 5 is a plan view partially in section. Fig. 6 is a sectional view on the line 6 6 of Fig. 1. Fig. 7 is an enlarged front elevation of the indenting-tool and the feeding devices. Fig. 8 is a section on the line 8 8 of Fig. 4. Fig. 9 is a detail view, partially in section, of the device for positioning the indenting-tool or returning it to its normal position after it has completed an indentation. Fig. 10 is a perspective view showing the rocking lever in which the tool-holder is pivoted. Fig. 11 is a perspective view of the tool-holder. Fig. 12 is an end elevation, partially in section, of the tool-holder in place on the rocking lever. Figs. 13, 14, and 15 illustrate the feeding devices. Fig. 16 illustrates in perspective the clutch for the shaft which locks the work-sup-

port. Fig. 17 represents in section said last-mentioned shaft and the parts thereon.

In carrying out my invention, one form of which is embodied in the machine illustrated in the accompanying drawings and which I am about to describe, it will be understood that I may use different forms of the various parts thereof and change the details to suit any particular requirements.

Referring to the drawings, *a* indicates the standard, upon which the operative parts of my machine are mounted, the standard being equipped with a suitable base (not shown) and with a bed *a'* upon its upper end, to which the base-plate *b* of the frame *b'* is secured by bolts *a'*.

The frame is provided with two upright rearwardly-extending brackets *b*²*b*², in which is mounted a power-shaft *c*, equipped at one end with a driving-wheel *c'* and at the other end with a balance or fly wheel *c*². The power may be applied to the driving-wheel *c'* through a belt driven from any convenient shaft, as by a counter-shaft mounted in the lower part of the standard of the machine, there being, if desired, suitable clutch mechanisms for connecting and disconnecting the continuous power to and from the counter-shaft, this latter device not being shown, as it is common and needs no illustration.

Upon the driving-shaft *c* are mounted the cams for operating the movable parts of the machine and which I will hereinafter describe in detail.

The upper part of the frame *b'* is widened to form a head or slideway *d*, in which reciprocates the feed-slide *d'*, there being suitable strips *d*² secured to the slideway to maintain the slide therein. The slide *d'* is formed with transverse parallel guides *d*³ to receive a sliding block *d*⁴, and projecting upward from the said block *d*⁴ is a threaded pin *d*⁵, passing through a slot *d*⁶ in a hand-lever *d*⁷, pivoted at *d*⁸ to the slide *d'*, at the left-hand end thereof. The lever *d*⁷ slides upon a plate *d*⁹, secured to the slide *d'* and having a series of apertures *d*¹⁰ to receive stop-pins *d*¹¹ *d*¹¹, which limit the movements of the lever *d*⁷ or lock it in any desired position.

Pivoted to the head or slideway *d*, so as to project transversely across the lever *d*⁷, is a

cam-lever e , having a slotted end e' , through the slot of which the pin d^5 passes, the upper end of the pin being provided with suitable washers and a nut d^12 . The lever e is provided with an enlarged hub or bearing e^2 , surrounding the pivot-pin, which projects upward from the side of the head or slideway and has a nut thereon to hold it in place. The rear end e^3 of the lever projects rearwardly over the driving-shaft c and is provided with a roller e^4 , extending down into a cam-groove f' in a cam-disk f on the power-shaft c . When the power-shaft is rotated, the rotation of the cam-disk causes the oscillation of the lever e and the consequent reciprocation of the feed-slide d' .

By swinging the hand-lever d^7 upon its pivot toward and from the pivot-pin of the lever e the length of the movement of the feed-slide may be varied as desired and as will be readily understood.

The feed-slide is provided with a downwardly-projecting and laterally-extended supporting-plate g , upon which are mounted the feeding devices. The forwardly-projecting end g' of the supporting-plate g has an upper vertically-stationary and longitudinally-adjustable jaw or gage g^2 , against which the upper is to be placed and which comprises a portion of the feeding devices, it being secured in place by screws g^3 . The vertically-movable and forwardly-extended jaw or presser-foot g^4 of the gripping device is located directly below the gage and coacts therewith to grip the work and feed it forward positively, as will be hereinafter fully described. The presser-foot g^4 has a lug g^{10} to be grasped by the attendant in depressing it, and is secured to a lever g^5 , pivoted by a large-headed screw g^6 to the supporting-plate g , said lever having on its rear end a segmental rack g^7 , as shown in detail in Fig. 13. This segmental rack g^7 intermeshes with a pinion h' , rigidly secured to a shaft h , having one end journaled in the supporting-plate g and its other end journaled in a bracket g^8 , secured to the supporting-plate g . The said shaft h is provided with a ratchet-wheel h^2 and a disk h^3 , arranged side by side and both secured rigidly thereto by a key or spline. Said ratchet-wheel has its hub extended to form a sleeve h^4 , extending substantially to the end of the shaft h , and upon the said sleeve and mounted to turn thereon is a cam-lever h^5 , having its rear end provided with a roller h^6 , resting upon a cam h^7 , rigidly secured to the driving-shaft c , next to the hub of the balance-wheel. The lever h^5 is also provided with a sleeve-like hub h^8 , which extends through the bracket g^8 , the end of the shaft being reduced and threaded, as at h^9 , to receive a washer h^{10} and a nut h^{11} for securing said parts in place. The lever h^5 is provided with two dogs or pawls h^{12} , either of which is adapted to engage the teeth of the ratchet-wheel h^2 at certain predetermined times, being forced toward said ratchet-wheel

by a spring h^{13} , secured to an arm on the said lever. The bracket g^8 is provided with a curved shield g^9 , projecting across the ratchet-wheel h^2 and resting loosely upon the disk h^3 , which is provided for this purpose. When the cam is in such position that the roller h^6 on the rear end of the lever h^5 is elevated, the pawls h^{12} are carried below the lower edge 75 of the shield g^9 , so as to be thrust inward by their springs h^{13} to engage the ratchet-wheel h^2 and lock it against movement. This in turn prevents the rotation of the pinion h' , and consequently any movement of the presser-foot; 80 but when the power-shaft is rotated so that the spring g^{10} , connected to the arm h^{14} of the lever h^5 and the supporting-plate g , has drawn the forward end of the said lever h^5 upward the pawls or dogs ride up upon the shield g^9 , and 85 the ratchet-wheel, the pinion h' , and the lever g^5 , with the presser-foot, are free to move. The cam h^7 and the cam-groove f' in the cam f are so related that when the forward feed is taking place the presser-foot is locked and when 90 the rear feed or return movement of the presser-foot and the gage is taking place the presser-foot is unlocked and is free to move vertically. Thus I provide that the work is gripped positively and rigidly to feed it forward, the grip being loosened immediately as the gage and presser-foot, which constitute the gripping-jaw, begin their backward movement. When the backward movement of the feed has taken place and the lever h^5 is operated by the cam h^7 , the pawls h^{12} are carried below the shield g^9 , as previously stated, and, 95 engaging the ratchet-wheel h^2 , give it a slight partial rotation, and it in turn gives a slight movement to the pinion h' , so that the forward end of the lever g^6 is raised by reason 100 of its rear end being provided with the segmental rack g^7 , in mesh with the said pinion. This causes the jaw g^4 to clamp the work against the opposite jaw g^2 , and the jaws remain locked as long as the pawls h^{12} engage the ratchet-wheel h^2 . As soon as the cam h^7 reaches the proper position and the pawls ride up on the shield the light spring h^{20} , (see Fig. 3,) connected to the head and to the end of 105 the lever g^6 , causes the jaw g^4 to release the work and press lightly against the sole, thus permitting the two jaws to slide backward to take a fresh grip.

I shall now describe the indenting-tool and 110 the means for operating it.

Pivoted by a pin i to a slide l , operating in a slideway l' in the frame of the machine and which slide has a hub l^2 projecting through a slot in the frame of the machine, below the 115 slideway d , is a lever i' , having its rear extended end provided with a roller i^2 , projecting into a cam-slot f^2 in the cam-disk f . The rear end of the lever i' is normally held upward by a spring i^3 , having one end connected 120 to the lever and the other end connected to a pin i^4 , projecting out from the slideway d . The forward end of the lever i' is provided with two internally-threaded ears or lugs $i^5 i^5$,

one arranged vertically above the other to receive between them the tool-holder j , which is provided with conical sockets $j' j''$ to receive the pointed ends of two screws $j^3 j^2$, passing through the ears i^5 . Thus the tool-holder has a vertical movement around the screw-pin i and a horizontal movement about the axes of the screws j^2 .

The lever i' is provided with a stop i^6 and a flat spring i^7 , whose rear end is secured to a projection i^8 on the said lever, and between the stop and the spring extends a projection j^2 of the tool-holder j , so that under normal conditions the tool-holder and the lever are held so as to move together vertically, though the tool-holder may have an independent horizontal movement about the axes of the screws j^2 . The forward end of the tool-holder projects forwardly and upwardly, as shown in Figs. 4 and 11, and is provided with two lugs j^3 to receive between them the indenting-tool k , there being a screw k' passed through said lugs and through a slot in the indenting-tool, so as to lock them together after the indenting-tool has been properly adjusted.

The tool-holder has a downwardly-projecting tail j^4 , with a wedge-shaped or pointed end j^5 , and sliding in guides $m' m'$ is a slide m , having a block m^2 , with an angular recess m^3 , to receive the said end g^5 . The slide m has an arm m^4 , equipped with a roller m^5 , extending into a cam-groove f^3 in the cam-disk f .

When the indenting-tool is depressed, it is free to engage the stitches in the welt and slide between them, the spring i^7 permitting this, so that it is necessary to provide a device of the nature just described for engaging the tool-holder and positioning it, or, in other words, causing it to assume its normal position each time after it is operated. Hence the cam-grooves $f^2 f^3$ in the cam-disk are so formed that the tool is first depressed before the readjusting device, having the angular recess m^3 , is fed forward, so as to position the tool-holder ready for another operation.

I find it advisable not only to have a downward movement of the tool-holder and to allow of a horizontal vibration of the tool, but that it is frequently necessary to give the tool a motion toward and from the work, and to this end I secure to the projecting end of the pin i (see Fig. 6) a block or roller n , by means of a screw n' , threaded into an aperture in the pin i .

The block or roller n lies in a socket in a lever pivoted at n^2 to the frame of the machine and having an upwardly-projecting arm n^3 and a rearwardly-projecting arm n^4 , the latter being provided with a roller n^5 , projecting into a cam-slot f^4 in the side of the disk f opposite the cam-grooves $f^2 f^3$. The cam-slot f^4 is so formed that as the tool is being depressed into engagement with the upper edge of the welt it is at the same time given a slightly-forward movement, so as to project in under the bulging part of the upper on the last.

The table or work-support consists of a bar o , formed at its upper end o' to receive the work and sliding in a guideway in a bracket p , secured to an extension b^4 of the frame b' , there being guides p' extending over the bar, so as to hold it in place. Its rear face is formed with rack-teeth which engage a pinion p^2 , formed on or secured to a shaft p^3 . (Shown in dotted lines in Fig. 8.) The bracket p is formed cylindrically to provide a bearing for the shaft p^3 , it being extended out to the left to form a bearing p^4 for the left-hand end of the shaft. The bracket p is likewise provided with a downwardly-projecting and forwardly-extending arm p^5 , through which the lower reduced and threaded end o^2 of the table passes, said threaded portion being provided with a milled nut o^3 , between which and a collar o^4 a spiral spring o^5 is inserted, so as to hold the table upward with a yielding pressure.

Nuts o^6 are placed upon the threaded portion o^2 of the table to act as stops for the latter in its upward movement. The lower end of the said threaded portion o^2 is preferably connected by any suitable means, as a chain, with a treadle (not shown) mounted in the base of the machine.

I provide means for locking the table against movement during the time that the indenting-tool is being depressed into engagement with the work, it consisting of a clutch mounted upon the shaft p^4 , as shown in Fig. 5. The clutch is formed of two collars $q' q^2$, joined together in one piece, the collar q^2 having an upwardly-projecting stop q^3 and the collar q' having an outwardly-projecting stop q^4 , engaging the bracket p^4 . These collars are placed upon a sleeve p^6 , rigidly secured to the shaft.

A small slide r , operating in a slideway on the left-hand face of the frame b' , as shown in Fig. 8, is provided with a roller r^2 , held in engagement with the cam-disk by a suitable spring. (Not shown.) The forward end of the slide is provided with an adjustable screw r^3 , which is moved forward to abut against the stop q^3 and give such a twist to the clutch as to lock it and the shaft rigidly together, so as to hold the table against movement.

The operation of the device is as follows. The parts being in the positions illustrated in Figs. 1, 2, 3, 4, 5, and 8, the work may be placed between the indenting-tool and the table and between the presser-foot and the gage by depressing the table and the presser-foot, the upper being placed against the gage. This may be accomplished simultaneously by connecting the lever g^5 with the link s , extending from the table-bar to the foot-lever. The work having been placed in the machine and power being imparted to the wheels c and the driving-shaft c , the parts perform the following functions: As the shaft revolves the roller h^6 is carried upward by the cam h^7 and the presser-foot is moved upward to clasp the work firmly between it and the gage. At the

same time or immediately thereafter the lever *e* is actuated to throw the feed-slide, together with the gage and the presser-foot, to the left, so as to feed the work beneath the indenting-tool. When the feeding devices have traversed one-half of their movement, the indenting-tool is allowed to be drawn downward by its spring, so as to rest yieldingly upon the work, and as the work slides under it it drops 5 into one of the depressions between the stitches and is carried along with the work until the feeding devices stop their movement. A further movement of the power-shaft causes the rear end of the lever *i*' to be given a final 10 tilt, so as to throw the tool-holder forward and down until the indenting-tool makes a dent or depression in the welt and between the two adjacent stitches. A still further movement of the power-shaft causes the feed-slide to re- 15 turn the feeding devices to their original positions with a quick positive movement, and at the same time the readjusting device is carried forward so as to engage the tool-holder and return it to its normal position. Just 20 before the indenting-tool was caused to sink into the welt the slide *r* was moved forward, so as to engage the clutch and lock the table against movement, and immediately after the back feed takes place the slide *r* is drawn away 25 from the clutch, so as to allow the table to hold 30 the work against the indenting-tool with a yielding pressure to permit the readjusting device to carry the indenting-tool and the work backward until the tool-holder is in its 35 normal position. Hence if the stitch is abnormally short the work is positioned as well as the tool, so that the tool will be able to locate the next normal stitch. The readjusting device therefore not only positions the tool, 40 but positions the work as well. The power- shaft at this time has completed almost one revolution, and as it is turned the remainder of a revolution the indenting-tool is raised to its inoperative position. Thus it will be seen 45 that the devices are again ready to feed the work forward and indent it, as I have just described.

Having thus explained the nature of the invention and described a way of constructing 50 and using the same, though without attempting to set forth all of the forms in which it may be made or all of the modes of its use, I declare that what I claim is—

1. In a machine for separating the stitches 55 in boot and shoe soles after the sewing has been completed, the combination with means for clamping and feeding the work positively in one direction only, of an indenting-tool movably mounted above the work and constructed and arranged to descend between two stitches and be carried along with the work and means for actuating the tool to indent the work.

2. In a machine for separating the stitches 60 in boot and shoe soles, the combination of means for feeding the work, an operating-le-

ver, an indenting-tool independent of said feeding means pivoted in the lever to swing freely in the line of feed by the engagement of the work therewith, and means for actuating the lever to cause the tool to indent the work.

3. In a machine for separating the stitches in boot and shoe soles, the combination of means for feeding the work, an indenting-tool mounted loosely to swing laterally by the engagement of the work therewith, means for actuating the tool to indent the work, and means for laterally positioning said tool after it has been operated.

4. In a machine for separating the stitches in boot and shoe soles, the combination with an indenting-tool constructed and arranged to move in the line of feed and means for moving said tool toward and from the work, 85 of means for positively positioning said tool after it has indented the work.

5. In a machine for separating the stitches in boot and shoe soles, the combination with an indenting-tool movable in the line of feed, 90c of means for depressing and raising said tool, and additional means for positioning said tool after each operation.

6. In a machine for separating the stitches in boot and shoe soles, the combination with 95 an indenting-tool movable in the line of feed, of means for depressing and raising said tool, and a slide for engaging and positioning said tool.

7. In a machine for separating the stitches in boot and shoe soles, the combination with an operating-lever, an indenting-tool, and a tool-holder pivoted to said lever to be swung freely by the work, of means for positioning said tool-holder after it has swung with the 100 work in the line of feed.

8. In a machine for separating the stitches in boot and shoe soles, in combination, an indenting or separating tool, a tool-holder pivoted to swing in the line of feed, means for raising and depressing said tool-holder, and additional means positively positioning the tool-holder.

9. In a machine for separating the stitches in boot and shoe soles, the combination with 110 an indenting-tool constructed and arranged to locate the stitches and separate them, of two movable reciprocating jaws for clamping the work and feeding it positively underneath the indenting-tool.

10. In a machine for separating the stitches in boot and shoe soles, the combination with a work support or table and an indenting-tool constructed and arranged to locate and separate the stitches and temporarily clamp 115 the work against the work-support, of two movable jaws constructed and arranged to feed the work between the indenting-tool and the work-support, and means for operating said jaws to feed the work and then return.

11. In a machine for separating the stitches in boot and shoe soles, the combination with

an indenting-tool, of a gage, and a presser-foot, both forming a part of the feeding devices, and means for positively moving said feeding devices forward with the work and backward without it.

12. In a machine for separating the stitches in boot and shoe soles, the combination with an indenting-tool, of a gage, and a presser-foot, both forming a part of the feeding devices, means for positively moving said feeding devices in one direction and then in the opposite direction, and means for locking the gage and presser-foot together during one movement and unlocking them during the opposite movement.

13. In a machine for separating the stitches in boot and shoe soles, the combination with an indenting-tool, of a feed-slide, and two locking-jaws reciprocatory in the lines of feed for feeding the work, said jaws being both mounted to move with the said feed-slide.

14. In a machine for separating the stitches in boot and shoe soles, the combination with an indenting-tool, of a feed-slide operated by a movable part of the machine, and two gripping-jaws mounted upon the feed-slide and constructed and arranged to grip the work to feed it under the indenting-tool, and to release it during their backward movement.

15. In a machine for separating the stitches in boot and shoe soles, the combination with an indenting-tool, and a reciprocating feed-slide, of two gripping-jaws mounted upon the feed-slide, and a cam-actuated lever constructed and arranged to coact with said gripping-jaws to cause the work to be gripped and moved in one direction and released when the jaws are moved in the opposite direction.

16. In a machine for separating the stitches in boot and shoe soles, the combination with the indenting-tool, and the feeding devices for the work, of a work support or table, comprising a depressible rack, a shaft having a pinion meshing with the rack, and a clutch constructed and arranged to lock the shaft

against rotation when the indenting-tool is being depressed.

17. In a machine for separating the stitches in boot and shoe soles, the combination with the indenting-tool, and the depressible work-support, of the reciprocatory jaws for clamping and feeding the work, means for depressing said work-support and means for separating said jaws whereby the work may be placed in the machine.

18. In a machine for separating the stitches in boot and shoe soles, the combination with a work-support, and feeding devices for the work, of an indenting-tool having provision for moving it forward under the bulging part of the upper, then allowing it to descend between the stitches to be carried along with the work, and then depressing it to separate the stitches.

19. A stitch locating and indenting machine comprising an indenting-tool, means for operating the same, and mechanism for causing the positioning of the work after the tool has indented it.

20. A stitch locating and indenting machine comprising an indenting-tool, means for operating the same, and mechanism for positioning the tool and the work, after the tool has indented the work.

21. A stitch locating and indenting machine comprising an indenting-tool, means for operating the same, means for feeding the work under the tool whereby the tool may drop between two stitches and be carried along with the work, and mechanism for positioning the tool and the work after the indentation has been made.

In testimony whereof I have signed my name to this specification, in the presence of two subscribing witnesses, this 16th day of November, A. D. 1896.
